No. 744,710.

PATENTED NOV. 24, 1903.

T. BARNES.

WATER GAGE SHIELD.

APPLICATION FILED MAY 9, 1903.

NO MODEL.

UNITED STATES PATENT OFFICE.

THOMAS BARNES, OF ANACONDA, MONTANA.

WATER-GAGE SHIELD.

SPECIFICATION forming part of Letters Patent No. 744,710, dated November 24, 1903.

Application filed May 9, 1903. Serial No. 156,457. (No model.)

To all whom it may concern:

Be it known that I, THOMAS BARNES, a citizen of the United States, residing at Anaconda, in the county of Deerlodge and State of Montana, have invented a new and useful Water-Gage Shield, of which the following is a specification.

This invention is a shield for water-gage tubes, the object being to provide a shield for the purpose of protecting water-gage tubes against breakage by contact, a still further object being to provide a shield which will afford a clear view of the water-tube at all times, so that the condition of water within the boiler can be readily seen.

Another object of the invention is to provide a water-tube shield which can be quickly and easily attached to or detached from the boiler.

With these objects in view the invention consists, essentially, in providing an open-sided frame having glass panels, said open-sided frame being adapted to envelop the water-tube, and means connected to the boiler for supporting the said frame.

The invention consists also in certain details of construction and novelties of combination, all of which will be fully described hereinafter and pointed out in the claims.

In the drawings forming part of this specification, Figure 1 is a perspective view showing the practical application of my invention. Fig. 2 is a detail perspective view showing the upper end of the frame having the glass panels arranged therein. Fig. 3 is a horizontal sectional view of the said frame and panels. Fig. 4 is a side elevation partly in section and showing the manner of supporting the frame. Fig. 5 is the plate from which the frame is supported. Fig. 6 is an elevation of the bracket carrying the plate. Fig. 7 is an inverted perspective view of the coping arranged upon the top of the frame. Fig. 8 is a sectional view illustrating a slightly modified form of construction.

In carrying out my invention I employ an open-sided frame comprising the upright pieces A, the top connecting-pieces B, and the bottom connecting-pieces C. The upright pieces A are grooved vertically, as shown at A', the top connecting-pieces slotted, as shown

at B', and the bottom connecting-pieces C are also grooved, as shown at C', said grooves and slots being arranged to receive the glass panels D, which are slid into the frames from the top, and it will be noted that I employ two pieces of glass, thereby rendering the protection doubly effective. After the glass panels have been arranged in the frame a grooved coping E is arranged upon the top of the frame and secured in any suitable manner, thereby holding the glass panel securely in position. This frame, as before stated, is open at one side, said opening being arranged at the rear, and this enables the frame to be arranged about the ordinary water-gage tube W, which is connected to the boiler in the usual or any approved manner, and for the purpose of supporting the shield in this position I provide the rear upright pieces A with downwardly-extending hooks F adjacent to the upper and lower ends of the uprights, which hooks are adapted to engage openings G, produced in the plate H, which is arranged adjacent the shield or head of the boiler, said plate being held by means of a bracket I, securely fastened to the head or shield of the boiler.

It will thus be understood from this description, when taken in connection with the accompanying drawings, that the shield can be quickly and easily connected to or disconnected from the boiler and that when in use it will entirely envelop the water-tube, thereby protecting it from contact with the exterior objects and thereby preventing breakage. It is also obvious that the water-tube is always exposed to view, and the condition of the water in the boiler can therefore be as easily ascertained as though the water-tube were not protected by any shield. In Fig. 8 I have shown a slightly-modified form of construction in which the frame is made in the form of a U and consists only of the rear upright pieces and the U-shaped top and bottom pieces. A U-shaped coping will of course be used with this construction, and the panels of glass will also be made U-shaped. In all other respects, however, the construction of the two frames will be identical.

It is obvious that a single panel of glass can be employed instead of a double panel,

and it will also be understood that the shield can be used in connection with a lubricator-tube as well as a water-gage tube.

Having thus fully described my invention, 5 what I claim as new, and desire to secure by Letters Patent, is—

1. A shield of the kind described, comprising an open-sided frame, having the double glass panels, the hooks connected to the frame, and the plate connected to the boiler, said plate having apertures adapted to be engaged by the hooks, as set forth.
2. A shield of the kind described, consisting

of a frame comprising the grooved upright pieces, the slotted top pieces, and grooved bottom pieces, the glass panels and the coping arranged upon the top of the frame, the hooks connected to the rear uprights, the plate having openings therein adapted to be engaged by the hooks, and the bracket for securing the plate, substantially as described. 20

THOMAS BARNES.
